UNITED STATES PATENT OFFICE.

VALENTINE ARNOLD, OF WOODVILLE, OHIO.

LIMEKILN.

Application filed April 9, 1919. Serial No. 288,739.

To all whom it may concern:

Be it known that I, VALENTINE ARNOLD, a citizen of Austria, and a resident of Woodville, in the county of Sandusky and State 5 of Ohio, have invented a certain new and useful Limekiln; and I do hereby declare the following to be a full, clear, and exact description of the invention, such as will enable others skilled in the art to which it 10 appertains to make and use the same, reference being had to the accompanying drawings, and to the characters of reference marked thereon, which form a part of this specification.

15 This invention relates to lime kilns, and has for its object the provision of an improved kiln of this character which has its lime burning chamber or retort of peculiar shape, whereby a more rapid and efficient 20 burning of the lime is accomplished than has heretofore been possible, and a material saving of fuel effected.

25 A further object is the provision, in a lime kiln, of a battery of slack arches at one side thereof or at each of opposite sides, and shaping the base portion of the lime 30 burning chamber to suit the number of slack arches employed, thereby enhancing the practicability, efficiency, and commercial value of apparatus of this character.

35 Further objects and advantages of the invention will be apparent from the following detailed description and drawings by persons skilled in the art.

40 While the invention, in its broader aspect, is capable of embodiment in numerous forms, a preferred embodiment is illustrated in the accompanying drawings, in which—

45 Figure 1 is a vertical section of a kiln embodying the invention, taken on the line w, w in Fig. 2. Fig. 2 is a similar section taken on the line x, x in Fig. 1. Fig. 3. is a cross-section on the line y, y in Fig. 1, and Fig. 4 is a top plan view of the kiln.

50 Referring to the drawings, 1 designates the stack of a kiln embodying the invention, which stack, in the present instance, rests on a base portion 2 and co-operates therewith to form a vertically-disposed retort passage 3, in which the burning of the lime takes place, as is well understood in the art.

The walls of the passage 3 are of peculiar contour and provide the passage, in succes-

sive order, from top to bottom thereof, with 55 the hopper-like head portion A, the restricted neck portion B, the body portion C, and the base or leg portion D, which latter, in the present instance, is disposed within the base portion 2 of the kiln structure. 60

The base portion 2 of the kiln is provided with the slack arches 4, which in the present instance, are arranged in sets of two at each of two opposite sides of the leg portion D of the retort passage, and each slack 65 arch has communication at its upper rear portion with said leg portion D through individual passages 5. Each arch also has an individual door 6 for the introducing of fuel. The leg portion D of the retort passage is of elongated form in cross-section, 70 as hereinafter more fully described, with its greatest dimension transverse, or at right angles, to the flame introducing passages 5, as shown in Fig. 3, thus making it possible 75 to place two or more furnaces 4 at each side of the retort.

The head portion A of the retort passage is preferably of circular form and is conically restricted to the upper edge of the 80 restricted neck portion B, which is also preferably circular in cross-section and of shallow depth, as shown.

The body and leg portions, C, D of the retort passage 3 in reality form the retort 85 or lime burning chamber thereof, and to facilitate such burning, are of peculiar form with respect to the lime introducing neck B. The walls of the passage 3 flares outward and downward from the lower end 90 of the neck portion B, as at a , and the two opposite walls of the chamber C, which walls are disposed over the furnace passages 5 and may for convenience be termed the side walls of the chamber, then incline 95 inward from the flared portion a to the upper end of the leg portion D, in the present instance, as at b , thus gradually restricting the width of the retort chamber to the narrowed form of the leg portion D, as 100 shown in Fig. 1. The end walls of the chamber C, however, instead of inclining inward and downward from the upper flared portion a , as do the side portions b , incline outward and downward, as at c , to broaden 105 the chamber C between said end walls, as shown in Fig. 2. As shown, the walls b and c are flat.

It is thus evident that the downward restricting of the opposite wall portions *b*, and the outward broadening of the opposed wall portions *c*, will change the portions *C* of the retort chamber from the circular outwardly flared part *a* to the enlarged and transverse elongated form of the leg portion *D* of said chamber, as perhaps best illustrated in Fig. 4. Or, in other words, the 10 retort chamber *C, D* gradually changes from restricted circular form at its top to enlarged elongated rectangular form at its bottom.

The transverse axes of the chamber *C* retain the same radial relation with respect 15 to the central longitudinal axis of the chamber from the top to the bottom thereof, or, in other words, the major or minor transverse axes of the chamber *C* at the various planes between the top and bottom of the 20 chamber are superimposed upon or coincide with one another.

The restricting of the neck portion *B* of the passage *3* with respect to the upper portion 25 of the retort chamber *C, D* is important, as the flames rising through the limestone contained in said chamber are caused to seek a central passage through the lime and not to follow the walls of the chamber, as would otherwise be the case, thereby distributing 30 a more uniform burning heat throughout the lime contained in the retort. It is also evident that the restricting of the passage *3* at *B* forms chokes at the top of the chamber which retards the flow of limestone into 35 the retort chamber and effects a loosening of such stone from its closely packed state as it passes downward through said chamber, thus facilitating the passage of the burning flames therethrough. The cross sectional area of the chamber *C* at the bottom 40 is considerably larger than at the top to permit loosening of the stone as it descends in the chamber. The chamber *C* may therefore, not only be termed a retort chamber, 45 but also an expansion chamber.

The lower part of the leg portion *D* of the retort passage is preferably restricted, and for such purpose has its end walls inwardly and downwardly inclined, as at *d*, 50 Fig. 2, and its side walls outwardly and downwardly inclined, as at *e*, Fig. 1. The lower restricted end of the retort passage *D* opens into a discharge hopper *7* that depends, in the present instance, from a plate 55 or frame part *8* provided in the base structure *2*. The hopper is preferably gradually restricted towards its lower end and opens at its bottom into a pit *9* provided in a sub-structure *10*, and the burned lime is drawn 60 from the kiln into the pit *9* through said discharge hopper.

It will be noted that the retort chamber *C* and fire boxes *4* are enclosed by a comparatively thick wall of masonry, the base of 65 which rests on tiers or pillars, but the dis-

charge hopper *7* depends below this thick wall of masonry and is constructed of comparatively thin metal to permit the contents of said hopper *7* to cool by radiation as it descends therein so as to prevent crystallization of the lime. 70

It is found in practice that the shaping of the retort passage of a lime burning kiln, substantially as herein described and shown in the drawings, very materially enhances 75 the burning efficiency thereof and considerably increases the output of the kiln, and also that the provision of two or more slack arches at opposite sides of the retort chamber adds to the working efficiency of the 80 kiln.

While I have herein shown and described one specific embodiment of my invention for illustrative purposes, and have disclosed and discussed in detail the construction and arrangement incident to one specific application thereof, it is to be understood that the invention is not limited to the mere detail or relative arrangement of the parts, but that deviations from the illustrated form or embodiment of the invention may be made without departing from the spirit of the 85 claims.

Having thus described my invention, what I claim as new, and desire to secure by Letters Patent, is— 95

1. In a continuous updraft lime kiln, a retort chamber having an open feeding mouth at its top and furnace flues and a discharge outlet at its lower portion, the mouth of said chamber being of substantially circular cross-sectional shape, the upper portion of said chamber immediately below its said mouth being flared abruptly outwardly to materially increased cross-sectional area to provide a gas choke capable of confining the burning therein, said chamber gradually widening in one direction and gradually narrowing in the other direction and at the same time gradually increasing in cross-sectional area from its said upper outwardly flared portion to its bottom portion where said flues are located, so that the lower portion of said chamber adjacent said flues is of elongated shape in cross section and is of considerably larger cross-sectional area that it is at its said mouth. 105

2. A continuous updraft lime kiln having its shaft shaped on the inside to form a substantially inverted cone-shaped feed hopper at the top, a restricted neck below said hopper, a retort chamber below said neck, the upper portion of said chamber immediately below said neck flaring abruptly outwardly to materially increased cross-sectional area to form a gas choke at the upper portion of said chamber to confine the burning within the latter, the walls of said chamber being flat below their flared portions and two opposed walls being inclined inwardly and 110

downwardly and the other two opposed walls being inclined outwardly and downwardly to gradually change the shape of said chamber to substantially rectangular shape at the bottom, the cross-sectional area of said chamber at the bottom being considerably larger than at the top, and furnaces disposed in the

shaft of said kiln and communicating with the bottom of said chamber through the longest opposed walls thereof.

In testimony whereof, I have hereunto signed my name to this specification.

10

VALENTINE ARNOLD.
